(57) **CLAIM**

The ornamental design for a flooring covering as shown and described.

DESCRIPTION

FIG. 1 is a front perspective view of the flooring covering; FIG. 2 is a front elevation view thereof; FIG. 3 is a rear elevation view thereof; FIG. 4 is a detailed view thereof; FIG. 5 is a right side view thereof; FIG. 6 is a left side view thereof; FIG. 7 is a top plan view thereof; and, FIG. 8 is a bottom plan view thereof.

The dash-dash broken lines in the figures depict boundaries of the article that form no part of the claimed design. The dash-dot-dash broken lines represent boundaries of the detailed views and form no part thereof.

1 Claim, 6 Drawing Sheets
